UNITED STATES PATENT OFFICE.

STEFAN WOJCIK, OF DETROIT, MICHIGAN, ASSIGNOR OF ONE-HALF TO JACOB LEWANDOWSKI, OF DETROIT, MICHIGAN.

CUE-TIP CLAMP.

1,381,385.

Specification of Letters Patent. Patented June 14, 1921.

Application filed November 30, 1920. Serial No. 427,433.

To all whom it may concern:

Be it known that I, STEFAN WOJCIK, a citizen of Poland, residing at Detroit, in the county of Wayne and State of Michigan, have invented certain new and useful Improvements in Cue-Tip Clamps, of which the following is a specification.

This invention relates to certain new and useful improvements in cue tip clamps and has for one of its objects to provide a device 10 for clamping a tip in position on the end of a cue stick during the cementing of the tip.

A further object of the invention resides 15 in the provision of a cue tip clamp wherein a clamp is adapted to be fixed to the outer end of a cue stick and carrying a tensioned sliding rod having a disk head at the outer end thereof for engagement with the tip 20 while a shifting lever for the tensioned rod is adapted to move the same to inoperative position relative to the cue tip during the mounting of the tip upon the cue stick.

With the above general objects in view 25 and others that will appear as the nature of the invention is better understood the same consists in the novel form, combination and arrangement of parts hereinafter more fully described, shown in the accompanying drawing and claimed.

In the drawing, wherein like reference characters designate corresponding parts throughout the several views,

Figure 1 is a side elevational view of the 35 outer end of a cue stick showing the present improved form of cue tip clamp operatively positioned thereon.

Fig. 2 is a top plan view of the clamp,

Fig. 3 is a front elevational view of the 40 cue stick and clamp,

Fig. 4 is a rear elevational view of the cue 45 stick and clamp showing the securing screw for the split ring, and

Fig. 5 is a horizontal sectional view taken 50 on line V—V of Fig. 1.

Referring more in detail to the accompanying drawing there is illustrated a cue 55 stick 1 having a leather or rubber tip 2 secured to the outer end thereof.

The tip 2 is adhesively secured to the stick 1 and to hold the tip in intimate contact with the end of the cue stick during the drying period of the cement or other adhesive, the clamp disclosed herein is employed.

The clamp embodies a tubular body 3 split

on one side thereof as at 4, shown in Fig. 4 and having a collar 5 at its inner end provided with lateral opposed ears 6 through which a tightening set screw 7 extends for securing the clamp 3 upon the stick against 60 relative movement.

A tensioned rod 8 is slidably associated with the tubular clamp 3, the same projecting through an apertured lug 9 carried by the outer end of the clamp opposite the split side thereof, the rod 8 being provided upon its outer end with a concaved disk head 10 overlying the tip 2 for engagement with the same during the clamping operation. To hold the disk head 10 in engagement with 70 the tip an expansion coil spring 11 surrounds the rod 8 between the lug 9 and the disk 12 secured to the rod by the transverse pin 13. A pair of arms 14 project from the tubular clamp 3 adjacent the inner end 75 thereof in longitudinal alinement with the lug 9 and have pivoted between the outer ends thereof on the pin 15, an angle lever 16 pivoted at its outer end as at 17 to the inner end of the rod 8 while the angle 80 lever 16 inwardly of the pivot pin 15 carries a finger piece 18.

The relative angle of the lever parts 16 and 18 permits the rod 8 to be moved inwardly by the spring 11 with the disk head 85 10 carried by the rod in engagement with the cue tip 2 while the finger piece 18 of the lever engages the adjacent edge of the clamp ring 5. The degree of tension of the spring 11 may be varied by shifting the tubular clamp 3 upon the cue stick 1 and holding the same in various positions by the clamping screw 7. In placing the tip 2 upon the end of the cue stick 1 after having provided sufficient cementing material upon 90 adjacent faces thereof, and assuming that the rod 8 is in the dotted line position shown in Fig. 1, the finger piece 18 is then moved on its pivot 15 with the side brackets 14 to the full line position shown in Fig. 1, 100 the spring holding the clamp in this position with the disk head 10 forcibly contacting the cue tip 2. In removing the clamp from the stick 1 the screw 7 is released whereupon the clamp may be moved outwardly from 105 inclosing relations with respect to the cue stick, with the cue tip properly adhering to the stick, and at which time the adjacent edges of the stick and tip may be finished and polished in any manner desired.

While there is herein shown and described the preferred embodiment of the present invention, it is nevertheless to be understood that minor changes may be made therein without departing from the spirit and scope of the invention as claimed.

What is claimed as new is:—

1. A cue tip clamp comprising a tubular clamping body, a clamping screw therefor, a tensioned rod carried by said tubular clamp, a disk head carried by the outer end of said rod overlying said clamp, an angle lever pivotally supported adjacent the inner end of the clamp having one end pivotally connected to the inner end of said tensioned rod with the other end providing a finger piece for shifting said rod.
- 10
- 15

2. A cue tip clamp of the type described comprising a tubular clamping body longitudinally split, a ring and clamping screw carried by said body, an apertured lug laterally projecting from the outer end of said clamp, a tensioned rod slidably extending through said lug, a pair of bracket arms laterally projecting from the inner end of said clamp in alignment with said apertured lug, and an angle lever pivoted between said bracket arms and articulated with the inner end of said rod, the free end of said lever constituting a finger piece for shifting the lever and tensioned rod connected therewith.

In testimony whereof I affix my signature.

STEFAN WOJCIK.
